L. H. BURNHAM

METHOD AND MEANS FOR COOLING ELECTRICAL APPARATUS

Filed Jan. 20, 1922

Inventor:
Locke H. Burnham,
by *Alfred S. Davis*,
His Attorney.

UNITED STATES PATENT OFFICE.

LOCKE H. BURNHAM, OF PITTSFIELD, MASSACHUSETTS, ASSIGNOR TO GENERAL ELECTRIC COMPANY, A CORPORATION OF NEW YORK.

METHOD AND MEANS FOR COOLING ELECTRICAL APPARATUS.

Application filed January 20, 1922. Serial No. 530,738.

To all whom it may concern:

Be it known that I, LOCKE H. BURNHAM, a citizen of the United States, residing at Pittsfield, in the county of Berkshire, State of Massachusetts, have invented certain new and useful Improvements in Methods and Means for Cooling Electrical Apparatus, of which the following is a specification.

My invention relates to the cooling of electrical apparatus and its general object is to provide an improved method adapted for this purpose, and an improved means for practicing this method. Some types of electrical apparatus develop a considerable amount of heat during periods of normal operation and this heat must be dissipated at a sufficient rate to prevent such an increase in the temperature of the apparatus as might cause injury. It is often true that the maximum safe load which a piece of electrical apparatus can carry may be increased by increasing the rate at which the heat generated in the apparatus is dissipated.

In connection with electrical apparatus which may generate an undesirable amount of heat, it is customary to provide some special arrangement for dissipating the excess heat. It is a particular object of the present invention to provide an improved method and apparatus whereby cooling currents of air may be induced and caused to come into contact with heat radiating surfaces which have received heat from the electrical apparatus; these surfaces giving up the heat to the moving air which acts efficiently to prevent undesirable temperatures in the electrical apparatus.

One type of electrical apparatus in connection with which my invention is adapted to be used with advantage is found in static transformers and, although the advantages of the invention for other purposes will be apparent, this embodiment thereof is explained in the following description and in the accompanying drawing in which Fig. 1 shows in elevation a static transformer equipped with heat radiators and with cooling means arranged in accordance with my invention; Fig. 2 is a plan view of apparatus shown in Fig. 1 with a blower and its motor omitted, and Fig. 3 is a plan view of one of the radiators with part of the cooling apparatus of my invention, a portion of the top of the radiator being broken away.

Like reference characters refer to similar parts in the different figures of the drawing. 55

In the embodiment of the invention shown in the drawing, a static transformer 1, including the transformer proper and its surrounding casing or container, is equipped with a plurality of heat radiators 2. As is customary, the casing of the transformer and the radiators and connections are filled with a suitable cooling and insulating medium such as an oil of high dielectric strength, the heat generated in the transformer causing a thermal circulation of the cooling medium through the radiators where this heat is transferred to the surrounding atmosphere and dissipated. 70

An air blower 3, driven by a motor 4, supplies air under pressure to a main feed pipe 5 which in turn supplies this air to distributing pipes 6. On each side of each radiator 2 is a delivery pipe 7 which is supplied with air under pressure from the distributing pipes 6. Each of these delivery pipes 7 is provided with a series of small openings 8 through which the air from within the pipe is blown in small currents or jets as indicated in Figs. 1 and 3. The openings 8 in each of the pipes 6 are so positioned as to direct the jets of air upwardly and inwardly against the adjacent side or face of the radiator and therefore at an acute angle thereto. It is preferable that the openings 8 be spaced along the pipes 7 so as to direct the air jets between the tubes of the radiators and thus distribute the moving air over a large radiating surface. 90

The jets of air issuing from the openings 8 draw along with them by friction large volumes of air from the space below and at the sides of the delivery pipes 7 as indicated by the arrows in Fig. 1 so that by locating these pipes 7 at some distance above the lower ends of the radiating surfaces, the volume of air passing over the heat radiating surfaces may be several times as great as that issuing from the openings 8 and supplied by the blower 3. A considerable radiating surface below and therefore behind the jets of air being blown from the openings 8 may be efficiently cooled by the air which is being drawn upwardly toward the jets. After this air reaches the jets, the air from both sources mingles and passes on under the influence of the jets to cool the

radiating surfaces above and in front of the jets. As the air is heated by the radiating surfaces, its natural tendency is to ascend in vertical paths and it is considered preferable to arrange the radiating surfaces in substantially vertical planes so that this tendency may assist rather than retard the movement of air induced by the jets.

An important feature of this invention is that a radiating surface may be cooled by a much greater quantity of moving air than that actually supplied by the blower. It follows that a blower large enough to supply all the air necessary to cool a given surface may be used in the cooling system of this invention to cool several times as great a surface. Heat radiating bodies have sometimes been surrounded by flues through which air has been passed from blowers to absorb heat. With such an arrangement, however, a blower must furnish all the air required. It has been found that in practicing my invention, at least three or four times as much radiating surface may be cooled by the same blower. This system of cooling is useful in locations where water is not plentiful and it also has the advantage, even where water is plentiful, that it is not subject to trouble such as may be caused by leaks in coils cooled by water. In some cases, the electrical apparatus is subject to widely fluctuating loads and therefore the amount of heat generated varies widely. Under such conditions, it may happen that during part of the time the radiating surfaces may be cooled sufficiently by the natural circulation of the surrounding air so that the blower may not be needed and may be stopped.

40 What I claim as new and desire to secure by Letters Patent of the United States, is:

1. In a method for cooling a radiating surface, the step which consists in inducing and directing a plurality of jets of air through and in contact with a surrounding body of

air and toward the radiating surface, the paths of said jets being at acute angles to the general plane of the surface, whereby air from said surrounding body of air is carried with the air of the jets along said surface in front of the jets.

2. In a method for cooling a radiating surface, the step which consists in inducing and directing a plurality of jets of air through and in contact with a surrounding body of air, said jets being directed toward one portion and away from another portion of the radiating surface, the paths of said jets being at acute angles to the general plane of the surface, whereby air from said surrounding body of air is moved along the portion of said surface behind the jets and thereafter with the air of said jets along the portion of said surface in front of said jets.

3. A cooling apparatus including a device having a radiating surface, means for supplying air under pressure, and means for directing a plurality of jets of said air through and in contact with a surrounding body of air and against the radiating surface at acute angles to the general plane of said surface.

4. A cooling apparatus including a device having a radiating surface, means for supplying air under pressure, and means for directing a plurality of jets of said air through and in contact with a surrounding body of air, said jets being directed toward one portion and away from another portion of the radiating surface, the paths of said jets being at acute angles to the general plane of the surface, whereby air from said surrounding body of air is moved along the portion of said surface behind the jets and thereafter with the air of said jets along the portion of said surface in front of said jets.

In witness whereof, I have hereunto set my hand this 18th day of Jan., 1922.

LOCKE H. BURNHAM.
